CLAIM

The ornamental design for a cycling bib, as shown and described.

DESCRIPTION

FIG. 1 is a perspective view of a cycling bib, showing our present invention;

FIG. 2 is a front elevational view of the present invention;

FIG. 3 is a rear elevational view of the present invention; and,

FIG. 4 is a right side elevational view, the left side elevational view being a mirror image thereof.

The broken lines shown in the figures are for the purpose of illustrating portions of the present invention that form no part of the claimed design.
